HEATING APPARATUS SWITCH

Earl K. Clark, Mansfield, Ohio, assignor to Westinghouse Electric Corporation, East Pittsburgh, Pa., a corporation of Pennsylvania

Application September 22, 1942, Serial No. 459,253

7 Claims. (Cl. 200—122)

1

This invention relates to heating apparatus and particularly to a control device therefor which is especially adapted to control the wattage input to the heating apparatus, and it has for an object to provide an improved device of the character set forth.

It is also an object of the invention to provide a control including a thermally-operated cycling switch wherein the wattage input to the heating apparatus is not materially affected by variations in ambient temperatures at the control and, therefore, it is not necessary to compensate for ambient temperature changes.

It is another object of the invention to provide a control including a thermally-operated cycling switch in which the switching cycles are of substantially uniform duration irrespective of normal changes in ambient temperatures effecting the control switch, and regardless of the selected wattage input to the heating apparatus to be controlled.

It is a still further object of the invention to provide a thermally-operated cycling switch in which the circuit-making and circuit-breaking switching operations are such that the time interval during which the circuit is closed may be adjusted to an extremely short interval to provide a minimum wattage input to the circuit controlled by the switch.

These and other objects are effected by my invention as will be apparent from the following description and claims taken in connection with the accompanying drawings, forming a part of this application, in which:

Fig. 1 is a perspective view of an electric cooking range in which the present invention is incorporated;

Fig. 2 is an elevational view of the present control with the cover thereof removed and parts shown in section;

Fig. 3 is a fragmentary elevational view corresponding to a portion of Fig. 2 and showing the movable parts in a position different from that in Fig. 2;

Fig. 4 is a sectional view taken substantially on the line IV—IV of Fig. 2;

Fig. 5 is a diagrammatic view of the control shown in the previous figures and including a wiring diagram to illustrate one application of the invention;

Figs. 6 and 7 are diagrammatic views similar to Fig. 5 but omitting the wiring diagram and showing the position of the switch contacts at different points in a cycle of operation of the control; and

2

Figs. 8 and 9 are time-temperature graphs illustrating the cycle of the thermal motor employed in the present control and showing the effect of changes in ambient temperature at the motor.

The control, generally indicated 10, comprises two sets of contacts 11 electrically connected in series as shown particularly in Fig. 5 and a thermal motor, generally indicated as 12 in Figure 2, which intermittently opens and closes these contacts. When both sets of contacts are closed, they complete a circuit for an electrical resistance element such as 13 in Fig. 5, which may be a surface heating element or an oven heating element of the range shown in Fig. 1. The control is adjustable so that the ratio between the length of time both sets of contacts are closed to the length of time one or the other of them is open to interrupt the circuit may be varied to provide a preselected wattage input to the resistance element 13.

The control is arranged in a compact housing 14 preferably made of insulating material and provided with a cover (not shown). The housing 14 may be conveniently mounted at the rear of the backsplasher of the range shown in Fig. 1, as illustrated by dotted lines, with its adjusting knob 15 accessible at the front. The housing carries two supply line terminals 16 having fixed contacts 17 which are engageable by movable contacts 18 carried by long springs 19. These springs are fixed to terminal brackets 21 and 22 at the lower end of the housing. The movable contacts 18 are moved into and out of engagement with their respective fixed contacts 17 by means of a cam 23. This cam is provided with notches 24 laterally offset relative to each other and which are adapted to receive integral lug portions 25 of the springs 19 when the control is set at its "off" position. The "off" position of the control 10 is shown in Fig. 2 where it will be noted that the lugs 25 are received in the notches 24, the natural bias of the springs holding contacts 17 and 18 open.

Cam 23 is fixed on a shaft 26, journaled in the rear wall of the housing, as shown in Fig. 4. By rotating the knob 15 from its "off" position, the lugs 25 ride on the cylindrical surface of the cam 23 to maintain the movable contacts 18 in engagement with fixed contacts 17 as shown in Fig. 3.

It will be understood that supply conductors, such as L₁ and L₂ of a conventional Edison three-wire system, are connected to the terminals 16 as shown in Fig. 5 and that the contacts 17 and 18 comprise a double-pole line switch to control

the supply of electricity to the thermal motor 12 and to the circuit controlled by the device of the present invention.

The thermal motor 12 is mounted in the lower portion of the housing and comprises a bimetal member 27 fixed to a bracket 28 which may be adjustably secured to the bottom wall of the housing to permit adjustment of the bimetal with respect to the cycling contacts 11. The upper free end of this bimetal has riveted thereto a U-shaped spring 29 which is received in an opening 31 provided in a horizontal bar 32 and prevents lost motion between the bimetal and bar.

The bimetal 27 is intermittently heated by means of a resistance 33 which is shown schematically as wrapped about the bimetal, although it is to be understood that the bimetal heating means may be associated with the bimetal in any suitable manner. When the resistance is energized to heat the bimetal, the bimetal bows to the left, as viewed in Fig. 2, and upon deenergization of the heater, the bimetal cools and moves to the right.

The right end of the bar 32, which, it will be understood is moved by the bimetal, is provided with a depending bracket 34 which carries a stop and switch-operating stud 35. This stud passes through and is journaled in an opening 36 provided in a plate 37 secured to the housing 14 by means of ears 38 integrally formed thereon and fastened to bosses 39 provided on the side wall of the housing.

By reference to Figs. 2 and 3, it will be noted that the travel of the bar 32 to the right is limited by engagement of the bracket 34 with the plate 37, as shown in Fig. 2, and travel to the left by engagement of shoulder 41 of the stud 35 with the plate 37, as shown in Fig. 3.

The stud 35 also operates a switch which controls the energization of the bimetal heating element 33. This switch comprises an adjustable contact screw 42 threaded into the side wall of the housing and a cooperating contact 43 carried by a snap-acting spring member 44, preferably of the so-called Valverde type. The snap-acting member 44 comprises three legs connected together at their ends, the outer legs 45 being made shorter than the central leg 46, as by crimping. The center leg 46 is fixed to plate 37 by means of a stud 47.

The operation of the switch, comprising contacts 42 and 43 for the bimetal heater 33 is briefly as follows: In Fig. 2 the parts are shown in the position they assume when the bimetal 27 has cooled sufficiently for the bar 32 to reach its extreme right position at which time the stud 35 has caused the snap-acting spring 44 to snap over to the position shown in this figure and close the contacts 42 and 43. With these contacts closed, a circuit is established from neutral conductor N of the supply source (Fig. 5), through the closed contacts 42-43, conductor 48, the heating element 33, conductor 49, terminal 22, right spring member 19 and closed contacts 18 and 17 of the line switch to L₁ of the supply line. With this circuit complete, heating element 33 heats the bimetal causing it to bow to the left, as viewed, in Fig. 2, to move the bar 32 and the stud 35 carried thereby to the position shown in Fig. 3 by which time nut 51 carried by the stud causes the snap-acting spring 44 to snap over to the position shown in Fig. 3 and open contacts 42 and 43 and thereby de-energize the bimetal heating element.

When the snap-acting spring 44 snaps over to open the contacts 42 and 43, the lower free end

of this spring engages an adjustable stop 52 carried by the plate 37, as shown in Fig. 3. It will be appreciated that the contact screw 42 and stop 52 may be adjusted relative to each other and to the lower free end of the snap-acting spring 44 so that the snap-acting spring may be made to operate between the limits determined by the length of travel of the switch-actuating stud 35.

With the bimetal heating element 33 deenergized, the bimetal 27 begins to cool and moves the bar 32 to the right until it reaches the position shown in Fig. 2 at which time the cycle described above will be repeated.

The bar is continuously reciprocated as long as the line switch contacts 17-18 are closed and as will appear later intermittently opens and closes the switch contacts 11 during the middle of its travel while effecting switching of contacts 42 and 43 at each end of its travel. In other words, the cycling switches 11 are actuated in spaced-time relation to the actuation of the switch 42-43. Each set of cycling contacts 11 include an adjustable contact 53 and a movable contact 54 biased toward its respective adjustable contact 53. The contacts 53 are simultaneously adjustable relative to their respective movable contacts 54 to vary the length of time both sets of contacts 53-54 are closed during each half cycle of the thermal motor 12 to increase or decrease the average wattage input to the resistance 13 controlled by these contacts. The manner of operating these contacts and adjusting them to vary the wattage input to the controlled circuit is described hereinafter.

The adjustable contacts 53 are carried by contact bars 55 which are fixed to the free ends of a U-shaped spring member 56 fixed to the upper end wall of the housing 14. This spring member serves to electrically connect the contact bars 55 and their contacts 53 and is so arranged that it biases the bars toward each other, to maintain adjustable stops or screws 57 carried thereby, in engagement with cams 58 and 59, respectively.

The cams 58 and 59, are fixed to the shaft 26, and are identical and arranged so that they simultaneously swing the contact bars 55 away from or toward each other as the shaft is turned by knob 15.

The movable contacts 54 are mounted on arms 61 which are, in turn, hingedly mounted on terminal brackets 62 and 22, respectively, by means of spring strips 63. These spring strips are so arranged that they tend to bias the contacts 54 into engagement with their respective adjustable contacts 53. The arms 61 extend through openings 64 and 65 provided in the reciprocating horizontal bar 32.

From the above description, it will be seen that with the line switch contacts 17 and 18 closed, the horizontal bar 32 continuously reciprocates and that by proper association of the openings 64 and 65 through which the arms 61 extend, these arms and their contacts 54 are alternately moved in a direction away from and, due to the bias of their hinge springs 63, toward their respective movable contacts 53.

Operation

It will be seen that in the condition shown in Fig. 2, with the control knob 15 set at "off," the line switch contacts 17 and 18 are held open and that the right-hand pair of contacts 53 and 54 of the cycling switch are also open. However, on turning the adjusting shaft from its "off" position to an active position, the condition repre-

5

sented in Fig. 5 will result, wherein the line switch contacts 17 and 18 are now closed causing energization of the bimetal heater 33 as already explained. It will be understood that turning of knob 15 from its "off" position causes cams 58 and 59 to swing the movable contacts 53 outwardly away from each other and toward their respective movable contacts 54. With the resistance 33 energized, the bimetal 27 begins to bow to the left and moves the horizontal bar 32 to the left permitting the right-hand contact arm 61 and its contact 54 to approach the right-hand adjustable contact 53 until the switches are in the position shown in Fig. 6. At this time both sets of the cycling contacts are closed since the bar 32 has not yet begun to move the left-hand contact arm 61. An energizing circuit for the resistance 13 is now complete. This circuit may be traced in Figs. 2 or 5 from one side L₁ of the supply line, closed contacts 17 and 18 of the line switch, through right spring 19, terminal bracket 22, right contact arm 61, closed cycling contacts 53 and 54 and their connecting spring 56, left contact arm 61, conductor 67 to one side of the heating element 13 and from the other side thereof through the left spring 19 and closed contacts 17 and 18 of the line switch to the other side L₂ of the supply line.

However, the bimetal continues to be heated until the bar reaches substantially its extreme left position, as shown in Fig. 3, but before this occurs, the left pair of cycling contacts 53 and 54 will have opened, as shown in Fig. 7, to interrupt the circuit just described. Thus, the energizing circuit for the heating element 13 is completed during a portion only of the time it takes the bar 32 to travel from right to left through the heating-up period of the bimetal 27. Similarly during the cooling-down period of the bimetal, the same sequence of operations described above in connection with the cycling switch contacts 53 and 54 is repeated except that the left pair of cycling contacts 53 and 54 close to complete the circuit and the right pair of contacts open to interrupt the circuit. It will be understood that cams 58 and 59 adjustably position the contacts 53 to fix the ratio between the period of time the contacts 53 and 54 are simultaneously closed to the period they are open for each cycle of the bar 32. Thus, if contacts 53 and 54 are both closed for one-half the time cycle of the bar 32, one-half wattage input is provided for the heating element 13.

For each complete cycle of the bimetal motor, that is, a complete reciprocation of the bar 32, the energizing circuit for the heating element is established twice and by selecting a bimetal 27 and heater which provides a two minute cycle, the heating element 13 is energized twice every two minutes. Thus, while this is an "on" and "off" control, the cycle is sufficiently short so that the effect is substantially the same as varying continuous wattage input. A further advantage arising from the present arrangement of the cycling contacts is that for each half cycle of the bimetal motor, one pair of cycling contacts completes the energizing circuit and the other pair of cycling contacts interrupts the circuit so that the life of these contacts is doubled as compared to cycling contacts wherein the same set of contacts interrupts and completes the circuit.

The cams 58 and 59, which position the contact arms 55 and their contacts 53 with respect to the associated movable contacts 54, are pref-

6

erably shaped so that, within the low wattage range of adjustment which provides relatively short "on" periods for the heating element 13, relatively great movement of the knob is required to effect a small change in the wattage input and the adjustment in the higher wattage input range is relatively coarse so that a small movement of the adjusting shaft effects a substantial change in the wattage input to the heating element 13. It is understood that the knob 15 will be provided with a suitable scale.

By providing the "on" period for the resistance element 13 at the center of the heating and cooling periods of the bimetal motor, it is possible to obtain a minimum time "on" interval to provide an extremely low wattage input to the resistance element. For example, if the "on" interval were at either end of the thermal cycle of the bimetal motor, the three following factors would be instrumental in adding to the minimum time "on" interval obtained at the minimum switch setting. These factors are:

(1) Annulment of the bimetal deflection as a result of engagement of the bimetal with the cycling switch contact. That is, movement of the bimetal is arrested until it develops enough force to overcome the spring bias exerted by the switch contact arm.

(2) Annulment of the bimetal deflection as a result of operating the bimetal motor switch, which must be snap-acting.

(3) The time interval required for the bimetal to change its direction of deflection at the end of its thermal cycle due to thermal storage and lag of the bimetal heating element.

The present control eliminates factor 2 in that the cycling contacts are actuated at a time other than when the bimetal is actuating the snap-acting bimetal switch and it also eliminates factor 3 since the bimetal actuates the cycling contacts in the middle of its travel, while the thermal storage and lag of the bimetal heating element is effective only at the ends of the heating and cooling periods of the bimetal.

The graphs of Figs. 8 and 9 illustrate the fact that normal changes in ambient temperature at the bimetal 27 have little effect on the cycling period of the bimetal and the wattage input to the resistance element 13 for any given adjustment of the knob 15, thereby obviating the need of ambient temperature compensation for the bimetal motor.

In the graphs, the bimetal temperature has been plotted against time for a complete cycle of the thermal motor. The lower horizontal line A represents the temperature at which the bimetal heater switch 42-43 closes and the upper horizontal line B the temperature at which this switch opens. Thus, beginning at the point C in the graph of Fig. 8, the bimetal temperature rises along the curve D until the upper temperature limit B is reached, as indicated by point E, at which time the switch 42-43 opens to deenergize the bimetal heater. The bimetal then cools along the curve F until the lower temperature limit A is reached at point G when the switch 42-43 again closes to begin a new cycle. The graph of Fig. 8 gives an approximate time-temperature indication with an assumed ambient temperature of 60° F. at the bimetal.

In Fig. 9 the same cycle has been plotted but with an assumed ambient temperature of 120° F. It will be noted that with the higher ambient temperature the heating period of the bimetal is shorter but the cooling period is longer than with

the lower ambient temperature, with the result that the length of the cycles is substantially the same for the different ambient temperatures.

As previously explained, both sets of cycling contacts 53-54 are closed during the middle of the travel of the bimetal on its heating and cooling periods, and the length of time these contacts are closed for each cycle of the bimetal determines the average wattage input to the heating element 13.

In Figs. 8 and 9, the horizontal lines H and I respectively indicate the lower and upper bimetal temperature limits between which the bimetal causes both sets of cycling contacts 53-54 to be closed for a particular setting of the knob 15. It will be understood that different settings of the knob change these limits to provide different average wattage inputs to the heating element 13. The points J, K, L, and M where the lines H and I intersect the curves D and F, represent the points at which the bimetal effects switching of the contacts 53 and 54. The horizontal distance between related points J, K, and L, M determines the time the contacts 53-54 are closed for a complete cycle of the bimetal. The ratio of the time between J and K, represented by X, to the total heating-up period, represented by Y gives the per cent of maximum wattage input to the heating element for the heating-up period of the bimetal. Similarly the ratio between the time X', the horizontal distance between L and M, to the cooling-down period Y' gives the per cent of maximum wattage input to the heating element for the cooling-down period of the bimetal. These ratios are substantially identical.

It will be noted from Figs. 8 and 9 that, since the portion of each of the heating and cooling curves during which the contacts are closed is located in the center of the curve, its slope will be substantially the same as the general slope of the complete heating or cooling curve. This is true even though the slope of the curve changes for different ambient temperatures. Accordingly, the percentage of time that the contacts are closed during each heating or cooling period remains substantially the same upon change in ambient temperature.

The present control is particularly adapted for use in a control system like that disclosed in Patent No. 2,399,423 of Edward Bletz, assigned to the assignee of the present invention. The Bletz control system includes a thermostatic switch which is responsive to the temperature of a body to be heated, such as a cooking vessel or the like placed on a surface heating element of a range, and arranged so that maximum wattage input is initially supplied to the heating element to rapidly heat the body. When the body reaches a predetermined temperature, it causes the thermostatic switch to open, and control of the energization of the heating element is shifted to a wattage selector which may, for example, be the present control.

As shown particularly in Figs. 2 and 5, such a thermostatic switch, generally indicated T, may be connected in parallel to the cycling contacts 53-54 so that when the thermostatic switch is closed these contacts are shunted and continuous energization of the resistance 13 is provided but when the temperature of the heated body and the thermostatic switch reaches a preselected value, the thermostatic switch opens and energization of the resistance 13 is then controlled by the cycling contacts 53-54.

While I have shown my invention in but one form, it will be obvious to those skilled in the art

that it is not so limited, but is susceptible of various changes and modifications without departing from the spirit thereof, and I desire, therefore, that only such limitations shall be placed thereupon as are specifically set forth in the appended claims.

What I claim is:

1. A control comprising a pair of series connected switches each including an adjustable contact and a movable contact, means for adjusting said adjustable contacts relative to their respective movable contacts, and reciprocating means for moving said movable contacts to close both pairs of contacts during the intermediate portion of its travel, to open one pair of contacts at one end of its travel and to open the other pair of contacts at the other end of its travel, said last-mentioned means comprising a thermal motor and a heater therefor, and switch means actuated by said motor and independent of said first-mentioned switches for controlling said heater.

2. A control device comprising a casing, a rotatable shaft in said casing and having handle means thereon for manually rotating said shaft, cam means carried by said shaft within said casing, adjustable contact arms disposed within said casing and biased into engagement with said cam means, a pair of movable contact arms mounted within said casing and having contact portions adapted to engage contact portions on said adjustable contact arms, means for moving said pair of movable contact arms in a regularly repeated cycle, said last-mentioned means being operable during each cycle to move one movable contact arm out of and into engagement with its associated contact portion and then to move the other movable contact arm out of and into engagement with its associated contact portion, said cam means being effective on adjustment of said shaft to position said contact portions of said adjustable contact arms to engage said movable contact portions for varying periods.

3. A control device for an electrically-energized element comprising first switch means for controlling the supply of electrical energy to said element, reciprocating means movable in a fixed path and actuating said switch means to cause alternate energization and deenergization of said element, the energization of said element taking place in a central portion of said path and deenergization of said element taking place in each end portion of said path, thermal-motor means including a temperature-responsive means and a heater therefor for moving said reciprocating means, and second switch means for controlling energization of said heater and actuated by said reciprocating means at the ends of said path.

4. A control device for an electrically-energized element comprising first switch means for controlling the supply of electrical energy to said element, reciprocating means for actuating said switch means to cause alternate energization and deenergization of said element, said reciprocating means actuating said switch means to close the circuit therethrough in the central portion of its travel and to open the circuit therethrough in each end portion of its travel, and thermal-motor means including a temperature-responsive means and a heater therefor for driving said reciprocating means, and second switch means for controlling the energization of said heater and actuated by said reciprocating means at the ends of its travel.

5. A control device for an electrically-ener-

gized element comprising first and second series connected switches, said switches each including an adjustable contact and a movable contact, means for adjusting said adjustable contacts relative to their respective movable contacts, a reciprocating member movable in a fixed path for moving said movable contacts and arranged to bring the movable contact of said first switch into engagement with its adjustable contact and subsequently move the movable contact of the second switch out of engagement with its adjustable contact when moving in one direction and to bring the movable contact of said second switch into engagement with its adjustable contact and subsequently move the movable contact of said first switch out of engagement with its adjustable contact when moving in the opposite direction, thermal-motor means for moving said reciprocating means in said path, said thermal-motor means including a switch actuated by said reciprocating means in spaced-time relation to the actuation of said first-mentioned switches.

6. An electrical control device comprising first switch means for opening and closing a circuit therethrough and including first and second actuating members each of which is adapted when actuated to open said circuit, reciprocating thermal-motor means for alternately actuating said members, said thermal-motor means including reciprocating temperature-responsive means and a heater therefor, and second switch means for initiating energization of said heater when said thermal-motor means reaches one end of its travel and for initiating deenergization of said heater when said thermal-motor means reaches the other end of its travel, said thermal-motor means being operable throughout one end portion of its travel to actuate one of said members to open the first switch means and throughout the other end portion of its travel to actuate the other member to open said first switch means, said first switch means being closed only during a central portion of the travel of said thermal-motor means.

7. A control comprising a pair of switches connected in series with each other, each of said

switches including an adjustable contact and a movable contact, means including a common manually-actuated member for adjusting said adjustable contacts with respect to said movable contacts, said last-mentioned means being operable to adjust both of said adjustable contacts toward their associated movable contacts upon movement of said member in one direction and away from the same upon movement in the opposite direction, motor means for moving said movable contacts into and out of engagement with said adjustable contacts in a regularly repeated cycle, said last-mentioned means being operable during each cycle to move one movable contact out of and into engagement with its associated adjustable contact while the other contacts are in engagement and then to move the other movable contact out of and into engagement with its associated adjustable contact while the first contacts remain in engagement, whereby the circuit through the series-connected switches is opened once by each switch during each cycle of operation and whereby both periods of circuit opening in each cycle are adjusted by said common manually-actuated member.
